GARMENT OR IRONING PRESS

Willis B. Rice, New York, N. Y., assignor, by
mesne assignments, to The American Laundry
Machinery Company, Cincinnati, Ohio, a cor-
poration of Ohio

Application July 17, 1930, Serial No. 468,487

4 Claims. (Cl. 38—40)

This invention relates to presses, more especially to fluid-motor operated garment or ironing presses, and to motor means for operating the press, including a two-hand control safety means to protect the operator by compelling him to use both hands until the coating press jaws are entirely closed on the work, or until the press head is closed on the buck.

It is an object to produce a press which, during closing movement, will immediately stop its closing motion if either or both hands be removed from the two control buttons or manuals but which, once its closing movement is completed, will remain closed by reason of fluid pressure until released and the press is opened by the operator who releases the pressure from the motor means.

It is a further object to produce a power ironing or garment press operated by fluid-pressure motor means having a non-locking or a non-straightening toggle or other operating or motion-transmitting means between the motor and press head which holds the press jaws in closed position by fluid pressure such as air or the like, 25 so that cushioned or resilient jaw compression on the work is maintained with full force until it is manually released at the will of the operator, whereupon the non-locking motion-transmitting means returns or opens to lift the press head.

Another object is to provide motor means having a motive-fluid supply system including a plurality of pressure feed lines which are governed by a two-hand control to actuate a motor means to close a press or actuate other machinery.

It is a further object to provide a fluid-pressure motor means having a piston which is held to the limit of its power stroke or travel by fluid pressure maintained against the piston by reason of a fluid-pressure line being maintained open by novel means rendered effective only approximately at the end of the power stroke of the motor means so that the air pressure supply line is open to the cylinder during the full period of jaw compression, and hence the piston is maintained under pressure by a column of fluid pressure derived from the source of air pressure or the like, as for example the air compressor and storage tank.

The pressing machine constituting this invention includes a normally-closed intake valve adapted to be opened manually through safety means to start the motor and hence may be called a motor-starting valve, and an automatic or motor-driven normally-closed valve to maintain the motor in its operated or pressing position.

and hence may be called a motor-control valve. The starting intake valve will not function unless manually held open by both hands until the press head closes and the control valve will not function to take over the control of the press until the press head fully closes.

In the operation of ironing presses, the press head or upper jaw is caused to exert heavy pressures against the work laid upon the buck or lower jaw and high temperatures are employed to heat the large-size press jaws. It is essential therefore in order to remove all possibility of an operator's hand being caught between the press head and the buck, that some means such as a two-hand control be provided to control the closing of the press. There is disclosed herein improvements in two-hand control motor-driven ironing presses for that purpose.

The accompanying drawings show an example of construction coming within the principle of the invention, and other equivalent forms and variations in construction may be employed without departing from the invention.

Figure 1 is a side elevation of an ironing press in open position and parts of the machine are shown in section.

Figure 2 is a cross section through an automatic or motor-driven or actuated control valve and it is shown in open-press position, the arrows showing the fluid pressure exhausting from the motor means; and Figure 3 shows the same valve in closed-press position with the arrows indicating the flow of fluid pressure, air or steam, to the motor means to close the press and hold it to closed position.

Figure 4 is a view, partially diagrammatic, of the two-hand control valve means in closed-press position. This view shows the motor-driven valve at the right and the two-hand control valve at the left with tube connections therebetween. This view is taken in part on the line 4—4 of Figure 5, and shows one button 14 of the two-hand control assembly, as well as exhaust or release button 16 to open the press.

Figure 5 is a front view of the two-hand control assembly mounted on the table of the garment or ironing press, as developed along the line 5—5 of Figure 4, and shows the spaced two-hand control buttons or manuals 14 and 15, the release button 16 to open the press being hidden from view behind the button 14.

The numeral 1 designates a press frame supporting a buck or lower press jaw 2 and mounting a press lever 3 pivoted at 4. The press lever 3 carries a press head or upper jaw 5 adapt-

ed to coat against the buck 2. The press lever 3 is actuated by jaw-operating means or mechanism as illustrated in the drawings or any other suitable means, as for example, a fluid-pressure motor comprising a cylinder 66 in which a piston or connecting rod 6 is connected to a bell crank lever 7 having an arm 8 connected to the rear end of the press lever 3 by a link 10. The arm 8 and link 10 thus form a non-straightening toggle 8-10 by means of which the press head 5 may be swung up and down in relation to the buck 2 which opens and closes the press and produces jaw compression on the work to be ironed or pressed; and a spring 7a opens the press after air pressure is exhausted from the motor, inasmuch as the toggle 8-10 is proportioned, adjusted and set against locking or over-straightening.

The motor 66 is operated by compressed air 20 or other fluid pressure under the joint control of a manually two-hand operated valve 12 and an automatically operated motor-control valve 13 which are constructed in accordance with the principles of this invention, whereas any suitable 25 fluid motor means 66 and motion-transmitting or jaw-operating means 8-10 from the motor to one or the other of the press jaws, may be used.

The manual two-hand valve 12 is under the 30 control of two spaced control buttons or manuals 14 and 15 for directing air pressure to the cylinder 66 for closing the press, and one release button 16 for exhausting the air for opening the press is provided. The control buttons 14 and 15 are connected to a valve stem 17 by means of a 35 pair of links 18 and 19 which in effect constitute a small toggle joint. The button 15 operates a bell crank lever 20 pivoted on the frame 1 and this bell crank connects to one end of a cross link 22 exerting a side thrust or bracing effect upon a pivot or toggle knee 23 which connects the two links 18 and 19 attached to the first button 14.

The proportions of the toggle links 18 and 19 45 are such that they are normally held at such an angle to each other for open-press position that if the button 14 alone is pressed, the toggle 18-19 will bend or collapse further without operating or depressing the valve stem 17. Likewise 50 if the button 15 alone be pressed, the links 18 and 19 will be somewhat straightened but without operating or depressing the valve stem 17, because button 14 will yield upwardly. As soon, however, as the button 14 is depressed after 55 pressing the button 15, or by simultaneously pressing both buttons 14 and 15, the valve stem 17 will be pushed downwardly by reason of the fact that the side link 22 will have almost straightened the links 18 and 19 into alignment 60 and the link 22 will exert a lateral thrust upon the pivot 23 which will prevent the breaking of the toggle 18-19 so the latter will thrust downwardly on the valve stem 17 extending into the valve housing 12 under influence of the button 14.

Attached to the valve stem 17 is a valve head 25 working in a valve chamber 26 and also another valve head 27 working in a valve chamber 28. The valve chambers 26 and 28 are connected by a passageway 29 with which a pipe 30 70 communicates, while another pipe, an exhaust pipe 31, opens the chamber 26 to exhaust to atmosphere; and a passageway 32 connects the chamber 28 with an inlet source of motive fluid or compressed air supply 33 from a compressor 75 or supply tank, not shown.

The passageway 29 is provided with a valve seat 34 at its upper end against which the valve head 25 seats to close off communication between the passage 29 and the valve chamber 26 and hence close communication between pipes 5 30 and 31. A similar seat 35 is adapted to co-operate with or be closed by the valve head 27 when the valve head 25 is open or off of its seat 34. A spring 36 bearing upwardly against one of the valves urges the valve head 27 to its upper 10 or normally closed position and urges the valve 25 to its upper or normally open position affording communication between the pipe 30 and the exhaust pipe 31 which is the position of these parts when the press is open. 15

The spring 36 therefore normally holds the valve 25 open and the valve 27 closed, i. e., the spring causes the valves to return to their normal open-press positions whenever the valves are free to move or not held by the operator. As 20 soon, however, as the valve stem 17 is depressed, the valve head 25 closes the exhaust 31 by coming in contact with the upper seat 34 and at the same time the valve 27 unseats from the valve seat 35 and permits compressed air to be admitted from the pressure supply pipe 33 through the chamber 28 to the pipe 30, thus connecting the feed or power pipe line 33 to pipe 30, and then to the motor cylinder as will be explained.

Another or release valve stem 17 also extends 30 into the valve housing 12 and affords an operating connection between the release or press-opening button 16 and a pair of valves 125 and 127 disposed in valve chambers 126 and 128 which may be similar in all respects to the corresponding valve parts 25, 26, 27 and 28 heretofore explained, save that the chamber 128 communicates through an exhaust 31a to atmosphere while the chamber 126 communicates with the compressed air supply line 33. A spring 136 40 performs functions similar to the other spring 36 for this set of valves 125 and 127 normally holding the valve 125 open and the valve 127 closed so that through these valves a conduit 130 is normally connected with the compressed 45 air line 33 through the valve chamber 126 but is connected to the exhaust 31a only when the button 16 is depressed; and this is the position of these parts when the press is open.

A motor-control mechanism 13 will now be described, and it comprises a housing 13 within which a cylindrical valve core 39 turns, the latter having a segmental port or passage 40. A rotary-type valve is shown but any suitable valve may be used. Through the casing 13 are three ports 41, 42 and 43. The outside ports 41 and 43 connect with the conduits 30 and 130, and the central port 42 connects through a pipe 42a directly to the motor cylinder 66. The valve core 39 is under the control of lever means or bell crank 45 attached to the valve core 39. The bell crank 45 is connected by an operating link 45a to the toggle or other parts of the jaw-operating means to cause the valve core 39 to be moved counter-clockwise at the end of the press-opening movement to afford communication between the conduits 30 and 42a to exhaust the air from the cylinder 66 and open the press by the spring or weight means 7a.

The link 45a may be formed with a slot 47 70 which engages a pin 46 anchored to the toggle link 10. The slot 47 allows the press head 5 and motor to travel toward closed-press position with link 45a idling, while the operator holds down the two manuals 14 and 15. As the press head 75

closes, the pin 46 reaches the other or inner end of the slot 47 and actuates the valve core 39 by action of the leverage mechanism 8-10 to swing the valve core 39 clockwise to cause the port 48 to connect the conduit 130 with the pipe 42a. This final action of the control valve 13 serves to keep the cylinder 66 connected with the pressure supply pipe 33 after the operator releases the buttons and to maintain the press closed by air pressure.

In the use and operation of the press, the valve stem 17 is depressed by both buttons 14 and 15 to open the motor-starting or normally-closed intake valve 27, and it follows that compressed air is admitted from feed pipe 33 to the first air feed pipe 30 which is at that time in communication with the cylinder 66 through the port 40 of the valve 13 and flexible conduit 42a. Should, however, the operator now release one of the buttons 14 or 15 before the press jaw closing operation is complete, thus permitting the valve stem 17 to be snapped or return to up or closed position, the motor cylinder 66 is immediately connected with the exhaust 31 and the press is opened by a spring 7a or other means for the same purpose because the motive fluid no longer flows to the cylinder.

If, however, the valve stem 17 is maintained depressed until the press head 5 is completely closed upon the work and buck 2, then the final closing movement of the toggle 8-10 reverses the valve 13 placing the cylinder 66 in communication with the compressed air line 33 through the other or final feed line 130 and the chamber 126. The press head thereupon stays closed against the spring 7a because air pressure is maintained against the piston in the motor cylinder 66 despite the fact that the operator releases both buttons 14 and 15. Hence a column of motive fluid pressure is constantly applied to the motor 66 from feed lines 30 and 130 to keep the press closed through the non-straightening toggle 8-10 as shown in diagrammatic dotted line position in Figure 1 where the knee or knuckle of the toggle does not reach center or straight line position with the upper and lower toggle pivots.

When it is desired to open the press, the release button 16 is depressed and the conduit 130 is thereby connected with the exhaust 31a, Figure 4, which removes the pressure on the motor piston so that the spring 7a returns the press head to its open or up position. The spring 50 attached to arm 45 swings the valve 13 to exhaust or open-press position. The spring is not essential since as the press reaches its open position the pin 46 in the toggle link 10 will engage the link 45a to throw the valve 13 in open press position, Figure 2, and maintain the cylinder 66 open to atmosphere and exhaust by affording communication between the cylinder and the conduit 30 and hence to the exhaust port or pipe 31, and the motor is closed off from the air-pressure line 33.

The two fluid pressure feed or supply pipes 30 and 130 are in effect interposed between the single feed or supply lines 33 and 42a, the valve housing 12 being interconnected between the fluid pressure source pipe 33 for starting the motor, while the automatic or motor-control valve 13 is placed between the motor pipe 42a and the pair of feed or supply lines 30 and 130 to supply air to the motor at the end of the piston stroke. The valve 13 switches or changes the connection 75 from pipe 30 over to 130 whereby pipe 42a may

still draw pressure from the source pipe 33 after the combination valves 25 and 27 are sprung or snapped into closed position by spring means 36 when the operator releases the buttons 14 and 15.

If desired, a spring 50 may be employed to return the control-valve core 39 to open-press position as soon as the toggle 8-10 has moved or broken sufficiently to the right to release the pressure from between the press jaws so that only 10 a momentary depression of the button 16 is now necessary to cause the press to rapidly open all the way. The spring 50 keeps the valve core 39 to its full limited open-press position.

The motor-control valve first receives air from pipe 30 and then pipe 130 and in both instances directs the air through one pipe 42a to the motor cylinder 66. The motor piston is actuated through its complete stroke by air from pipe 30 going through valve 13 and its passage 40, but 20 as soon as the press head is actually down on the buck so close that the operator cannot get his hands between the jaws, then the valve lever 45 automatically shifts the valve core 39 to closed-press position with the result that air is then delivered to the piston from pipe 130. It now matters not that the operator releases one or both control buttons 14 and 15 and that spring 36 closes inlet valve 27 upwardly against its seat 30 35 to open exhaust valve 25 upwardly off its seat 30 34 because the control valve 13 is now in position to divert air pressure from feed pipe 33 to motor cylinder 66 quite independently of the two hand-control buttons and related valve means 12.

This ironing press is safe in operation and fills a need felt for improvements in this connection and rapidly irons the work. The press head is rapidly closed by the jaw-operating means and is opened by the spring opening means 7a. The motor-control valve 13 takes over the control of 40 the press from the operator and this valve 13 is effectively actuated by the lost-motion means 46-47 which connects the valve to the jaw-operating motor means. Other forms of motor-driven or mechanically-actuated valve-control 45 means may be used, but the illustrated pin and slot lost-motion connection discloses the principle of the invention.

Further reference is made to the unique motor-starting and releasing valve and pressure conduit system, wherein the single pressure inlet supply or source pipe 33 from a compressor or other source of motive fluid, leads to the valve housing 12. Two pipes 30 and 130 lead from this valve housing 12 to the motor-control valve 13 55 and, from the latter valve 13, a single pipe, usually a flexible connection 42a, transmits the motive fluid to the cylinder 66.

The pipe 30 first transmits the starting pressure to the motor 66 and continues to do so as long as the operator holds open the normally-closed intake valve 27 and holds closed the normally-open exhaust valve 25 carried on the common valve stem 17, and during this cycle of operation pressure is in the pipe 130 but is shut off at valve 13 from cylinder 66. Thereafter the lost-motion operating connection 46-47 rotates valve 13 whereupon its passage 40 opens pipe 130 to the motor to hold the piston down or to actuated position to hold the press jaws closed under resilient and yieldable compression without the aid of noisy opening mechanically locked joints or catches.

The release or press-opening valve unit 125-127 is positively held to normal position by a 75

stiff spring 136 against the pressure on exhaust valve head 127. That spring maintains the intake valve head 125 open and the release or exhaust valve head 127 closed. Hence this press-opening means also comprises two valve heads on a common stem 117 and the actuating button 16 is merely a simple or diagrammatic showing of manual means to thrust the stem 117 against the force of the heavy spring 136. Any suitable means to reduce the manual effort required by operator to unseat exhaust valve head 127 and seat intake valve head 125 may be used in connection with the valve stem 117 to cause the press to open.

15 Within the single valve housing 12 is contained the motor-starting valve means 25-27, the intake 27 of which is normally closed at one end of the housing against entry of pressure from supply pipe 33, while in the same housing 12 there is similarly, though reversely provided, the press-opening valve means 125-127, the intake 127 of which is normally open at the other end of the housing to open the pipe 33 to the pipe 130. The central passage 32 communicates with both sides 25 of the housing to transmit pressure to both valve units carried by the two stems 17 and 117.

The single housing 12 likewise has two exhaust ports 31 and 31a both of which function to open the press. Ordinarily the housing 12 has its two 30 exhaust ports opening directly to atmosphere and there is usually no necessity for piping either the exhaust 31 or 31a to the outside of the room or plant in which the press is operating. The exhaust 31 serves to instantly open the cylinder 35 66 to atmosphere and arrest the closing motion of the press head in event the operator should release either two-hand button 14 or 15 before the lost-motion or motor-controlled valve 13 takes over the control of the press.

40 On the other hand the exhaust port 31a is for releasing the pressure from the cylinder 66 after the press head has entirely closed down upon the work. The exhaust 31, therefore, releases the pressure from pipe 30 which was active in the cylinder 66 to initiate the piston or press closing 45 stroke, and the other exhaust 31a releases that pressure from pipe 130 which was standing in the cylinder to hold the press closed.

What is claimed is:

50 1. In a garment or ironing press, coacting press jaws, operating means including a fluid motor connected to one of the jaws for closing the press, a plurality of fluid pressure lines to operate said motor, each of said fluid pressure lines including a manual control valve, one of said valves being normally open and the other normally closed, a single valve means connected to both fluid pressure lines and positioned in the line between the manual controls and the motor, and 55 means operated by the press for actuating the single valve to first operate the motor from one pressure feed line and then hold it in closed po-

sition by use of fluid pressure from the other pressure feed line.

2. In a garment or ironing press, coacting press jaws and operating means therefor including a fluid motor connected to a jaw, a plurality of fluid pressure feed lines, an automatic valve to which the plurality of feed lines are connected and a single fluid connection from the valve to the motor, a single valve housing to which the feed lines are connected, a single fluid source line 10 connected with the valve housing, normally closed inlet valve means in the housing to admit fluid from the source line to one feed line, exhaust valve means in the valve housing to exhaust fluid pressure from another of the feed lines to 15 exhaust fluid pressure from the motor, a two-hand control button means operatively connected with the inlet valve, a single button means connected with the exhaust valve, and an operating connection provided between the automatic valve 20 and operating means to direct fluid pressure to the motor thru said inlet valve line to initially operate the motor and thereafter thru another line to hold the motor to operated position.

3. A garment or ironing press comprising co- 25 acting press jaws, fluid-motor means connected to one jaw to operate the press, a valve operatively connected to the motor means, a single fluid passage being provided from the valve to the motor means, two pressure feed lines connected to 30 the valve, whereby operation of the motor means actuates the valve to switch one feed line into communication with the single fluid passage and switch the other feed line out of communication with the passage, a motor-starting valve in the feed line which is connected to the motor when the press is open, and a press-opening valve in the other feed line.

4. A garment or ironing press comprising co- 40 acting press jaws including a head and buck, jaw-operating means including a fluid-pressure motor having a cylinder and piston operatively connected to the press head, two pressure feed lines, a motor-starting valve connected to one of the feed lines, manual means for actuating the 45 valve, a motor-control valve connected to the two feed lines and positioned between the motor-starting valve and the motor in the feed line having the valve, said motor control valve being normally open in the feed line having the motor-starting valve and closed to the other feed line, an automatic operating connection between the motor-control valve and the jaw-operating means to actuate the valve to close the motor-starting valve feed line and open the other feed 55 line, and a single pressure feed line from the motor-control valve to the cylinder, whereby the motor is started by pressure admitted by the motor-starting valve and is thereafter supplied by pressure admitted by the motor-control valve. 60

WILLIS B. RICE.
